UNITED STATES PATENT OFFICE.

CHARLES D. SKINNER, OF NEW KENSINGTON, PENNSYLVANIA.

FARE-RECORDING MECHANISM.

Application filed August 7, 1922. Serial No. 580,215.

To all whom it may concern:

Be it known that I, CHARLES D. SKINNER, a citizen of the United States, residing at New Kensington, in the county of Westmoreland and State of Pennsylvania, have invented certain new and useful Improvements in Fare-Recording Mechanism, of which the following is a specification.

My invention consists of an improvement 10 in railroad fare mechanism, and is particularly designed to provide means for registering or recording the fare of each passenger, providing a visible indicator and check, with means preventing unauthorized access to collected or deposited tickets, etc. The device in certain preferred forms is shown in the accompanying drawings, in which:

Fig. 1 is a view of a ticket display collecting box, in front elevation;

20 Fig. 2 is an end elevation;

Fig. 3 is a longitudinal vertical section on the line III—III of Fig. 2;

Fig. 4 is an enlarged cross section of one-half of the device;

25 Fig. 5 is a detail view showing a clip attachment on the top of the box;

Fig. 6 is a face view of one form of ticket for use with the invention;

30 Fig. 7 is a sectional view showing a plurality of seats and collecting mechanism for the several corresponding display boxes;

Fig. 8 is a detail view of a form of collecting and display box, for such system;

35 Fig. 9 is a similar view, partly broken away, showing the connection with a main conduit; and

Fig. 10 is a diagrammatic plan view, showing the invention as applied to a passenger car.

40 Referring to Sheet 1, a main rectangular casing 2 is mounted on top of a seat back A and contains a collecting drawer 3. Above the casing 2 is a top 4, hinged at 5 at one end and adapted to be locked by lock 6 of the drawer at the other end. Upon 45 unlocking, the drawer may be drawn out by its end handle 7, or the top may be swung upwardly on its hinge.

50 The top 4 is provided with a series of upwardly extending cavities or chambers a, b, c, and at each side of the longitudinal center are corresponding series of ticket receiving cavities d. The outside face of each such cavity is closed by a glass pane 8,

framed into the upper casing 9, and inwardly beyond the panes is a partition 10, at each side of the operating space or cavity a—b—c and of center line x, x, Fig. 4.

Each ticket receiving space d has a separately actuated opening and closing bottom 11 hinged to partition 10 at 12 and provided with a lever 13. Said lever is connected by link 14, pivoted at 15, and at 16 to operating rod 17 extending up through the top and provided with an operating button 18. 65 By lifting rod 17, the trap door or bottom 11 is lowered to deliver the ticket e into the drawer 3, the door then being closed by thrusting the rod downwardly. Any suitable ticket may be used, but I preferably 70 use one like that of Fig. 6, divided on the perforated or dotted line y, y.

In use, the conductor will take up the ticket from the passenger, remove the right hand coupon f, and give it back to him, as 75 a receipt. The left hand portion, bearing the destination, is then dropped through the slot 19 of top 9, into the cavity d, resting on the trap door 11, below the top 9, and thus in visible position inside the particular cavity d. The ticket will remain in such position until the passenger has reached his destination, when it may be dropped by the conductor into drawer 3, the device then being ready for another operation. 85

If desired, a clip 20 may be attached to the top of each cavity d, for temporarily holding the coupon f in convenient position.

The device, as above explained, is for 90 separate use, and may, of course, be provided with one, two, or three ticket cavities d at each side of its longitudinal center, for use and observation from either side, depending on the arrangement of the 95 seat backs A for travel in either direction.

I have shown on Sheet 2 means for collecting the contents of a series of collecting boxes, one series at each side of the aisle g of car G, and comprising a box for 100 each seat. The boxes themselves are of the same general construction just described, but, instead of a drawer 3, the lower casing is formed as a common conduit 21 leading downwardly into a vertical chute 22. Such chute is located in convenient position at the end of each seat, for use with the seat back in either position, and each chute leads 105

into the top of a common conveyor box 23, by which the several tickets may be delivered to a terminal receiving receptacle 24 having a lock-controlled door or drawer 25.

A conveyor belt 26 mounted on terminal wheels 27, 27, one having a crank 28, provides for carrying all of the tickets towards one end and delivering them into the receptacle 24, for collection.

The operation of the invention will be readily understood from the foregoing description. It provides for very accurate registry of each fare taken, ensures the positive use of each ticket, and gives a visible record of each transaction, whether by use of tickets bought from a ticket office or from the conductor. In the latter case, each cash fare passenger should be furnished with a ticket or coupon by the conductor, for use in the same manner as described, so that there is finally collected in the several drawers or collecting receptacles all of the tickets or other evidence of the business of a complete run.

Where three-cavity units are provided, the capacity of each double seat and one aisle or standing passenger is capable of being recorded, so that the maximum capacity of a car may be always counted. The device avoids the necessity of remembering the several individual passengers of a car, thus greatly relieving and simplifying the work of the conductor, and at the same time ensuring against carrying any passenger beyond his destination, or permitting any dispute as to payment of fare.

The advantages of the improvement will be appreciated by the traveling public and

railway operatives, and is a simple and effective means for the purpose intended.

It may be changed or varied in detail construction to suit various conditions of application by the skilled mechanic, but all such changes are to be considered as within the scope of the following claims.

What I claim is:

1. A double sided visible ticket receiver having outermost oppositely located ticket receivers each provided with a slotted opening, a lower ticket collecting holder, a hinged door between each ticket receiver and the holder, and door opening and closing mechanism between the receivers.

2. A ticket box adapted to be mounted upon or adjacent to the back of a seat, provided with a plurality of individual slotted cavities, a common lower lock-controlled receptacle, and a hinged lever-actuated door at the bottom of each cavity.

3. In combination with a series of individual ticket receiving boxes of the class described, a common conveyor conduit adapted to receive the contents of each box, and means for collecting the contents of several boxes at one terminal of the conveyor.

4. In combination with a series of individual ticket receiving boxes of the class described, a common conveyor conduit, a chute leading from each box into said conduit, a conveyor belt in the conduit, and means for actuating it, and a lock-controlled terminal receptacle for the conduit.

In testimony whereof I hereunto affix my signature.

CHAME D. SKINNER.
